PAPER GUIDING AND HOLDING MECHANISM FOR ACCOUNTING MACHINES

Walter A. Anderson, Bridgeport, Conn., assignor to Underwood Elliott Fisher Company, New York, N. Y., a corporation of Delaware

Application December 30, 1938, Serial No. 248,427

1 Claim. (Cl. 197—139)

This invention relates to paper carriages for accounting machines, and more particularly to means for guiding and holding the paper around the platen.

5 Frequently during insertion of rear fed paper around the platen, the paper catches on parts of the carriage.

It is an object of this invention, therefore, to provide a simple, inexpensive and effective means 10 for insuring smooth feeding of work sheets around the platen.

Another object is to provide such a means, that is readily adjustable laterally of the platen to suit forms of different widths, and also adjustable 15 toward or away from the platen to accommodate insertion of multiple forms.

With these and incidental objects in view, the invention consists in certain novel features of construction and combinations of parts, the 20 essential elements of which are set forth in appended claim, and preferred embodiments of which are hereinafter described with reference to the drawings which accompany and form part of the specification.

25 In the drawings:

Figure 1 is a perspective view of a carriage embodying the invention.

Figure 2 is a right side elevation showing a paper guide band adjusted to receive and hold 30 a single work sheet,

Figure 3 is a view similar to Figure 2, but with the band adjusted to accommodate a plurality of work sheets,

Figure 4 is an exploded perspective of the adjustable upper attaching means,

Figure 5 is a fragmental detail perspective of the adjustable lower attaching means,

Figure 6 is a fragmental perspective showing a modified form of the invention, and

Figure 7 is a detail sectional view of this modified form.

The invention is illustrated in connection with the type of carriage used on the machine disclosed in the application of Oscar J. Sundstrand, Serial No. 581,800, filed December 18, 1931, and 45 is adaptable for use on the type of carriage disclosed in United States Patent No. 2,060,954, issued to Oscar J. Sundstrand on November 17, 1936, or on that disclosed in United States applications of Walter A. Anderson, Serial Nos. 92,164 and 192,675, filed July 23, 1936, and February 26, 50 respectively.

Carriage in general

55 Referring to Figure 1, the carriage is mounted

for movement along a track 1. As the carriage moves from right to left, it is stopped in various columnar positions so that type bars (not shown) on the accounting machine may print on work sheets fed around a platen 2. The mechanism for tabulating the carriage from column to column and for returning it to its initial position is disclosed in application Serial No. 581,800. The platen may be rotated manually by knobs 3 secured to each end of a platen shaft 4, and may be rotated automatically during operations of the machine by a feed pawl (not shown) cooperating with teeth on a ratchet wheel 5 secured to shaft 4. The pawl and its operating mechanism is disclosed in Patent No. 2,060,954.

Mechanism for guiding and holding the paper

In introducing the paper, it is passed downwardly over a paper table 6 suitably secured between the carriage side walls and having its lower edge terminating a short distance in back of the platen (Figures 2 and 3). The lower edge of the paper engages between the platen and paper feed rolls 7 mounted in cradles such as 8 pivoted on brackets such as 9 secured to the rear side of paper table 6. Rolls 7 are tensioned clockwise against the platen by springs such as 10. Upon a slight turn of the platen by knobs 3, the paper is advanced between rollers 7 and platen 2, and upon further rotation of the platen is guided under and around the platen by bands 11, preferably formed of narrow, thin, and yielding material. Bands 11 encircle the lower and forward portions of the platen and are secured at their lower ends to hooks 12 (Figure 2) slidably embracing a rod 13 secured between the carriage side walls. Each hook has a slot 14 in which is inserted a spring ring 15 that frictionally embraces shaft 13 to hold the bands in their laterally adjusted positions.

The upper ends of the bands fit within slots 16 provided in brackets 17 (Figure 4) and are each provided with a pair of slots 18 through which pass screws 19 that thread into apertures 20 in brackets 17. Plates 21 of tempered spring material are secured on brackets 17 by rivets 22, and are each formed at their upper ends with lugs such as 23 and at their lower ends with clips such as 24 that embrace the upper and lower edges of a paper tear plate 25 (Figure 2). The tear plate is secured on a rod 26 pivoted at its opposite ends in the carriage side walls, and is provided at each end of its lower edge with a stud 27 that rests against a paper guide plate 28. The guide plate is provided at its opposite ends

with rearwardly projecting lugs 30 that rest against paper table 6. Upstanding ears 29 on the ends of plate 28 are pivoted on rod 26 adjacent the carriage side plates. Lugs 30 and studs 5 27 serve to hold the plates in spaced relation and at proper angles (Figures 2 and 3) for deflecting the paper upwardly as it leaves the platen.

When single forms are to be inserted around 10 the platen, bands 11 are adjusted by the screw and slot adjustment above described so that the clearance between the inner sides of the bands and the platen is just sufficient to permit smooth, easy insertion of a single sheet, as shown in Figure 2. When it is desirable to perform operations requiring joint insertion of several sheets, the bands are adjusted in the following manner. Brackets 17 are removed from tear plate 25 by 15 slightly depressing clips 24, then screws 19 are loosened and the brackets slid upwardly in slots 16 a sufficient distance so that when the screws are retightened and the brackets replaced on the tear plate, the clearance between the platen and the bands accommodates the number of sheets 20 to be inserted. Adjustment of the bands laterally, to suit the requirements of different width forms, is readily accomplished by detaching brackets 17, sliding the bands along rod 13 in accordance with the width of the form to be used, 25 and replacing the brackets on the tear plate at the new locations.

In the modified form of the invention shown 30 in Figure 6, the only variation in the structure from that above described is in the method of attaching the lower ends of the bands to rod 13, and in the provision of means which permits si-

multaneous adjustment of the bands around the platen. In this form of the invention, the lower ends of the bands are riveted to collars such as 31, which are slidable on the shaft but feathered to it for rotation therewith. Upon rotation of shaft 13, each of the bands are simultaneously moved toward or away from the platen to provide the necessary clearance in accordance with the number of forms to be inserted. In this form of the invention, shaft 13 extends through the right 10 carriage side wall and has fixed on its end a knob 32 for manual adjustment. A serrated disk 34, also fixed on the shaft adjacent the right side wall, cooperates with a spring detent 35 to hold the bands in adjusted position. 15

While the form of mechanism herein shown and described is admirably adapted to fulfill the objects primarily stated, it is to be understood that it is not intended to confine the invention to the one form of embodiment herein disclosed, 20 for it is susceptible of embodiment in various forms, all coming within the scope of the claim which follows.

What is claimed is:

In a paper carriage, a platen, a rotatable rod 25 under the platen, a tear plate above the platen, a plurality of paper guides lying around the platen and having their upper ends supported on the tear plate, their lower ends being connected to the rotatable rod so that rotation of the rod moves the guides toward or away from the platen to accommodate varying thicknesses of forms inserted around the platen, and manipulative means for rotating the rod. 30
